UNITED STATES PATENT OFFICE.

CHARLES D. McARTHUR, OF PITTSBURGH, PENNSYLVANIA.

MACHINE FOR BORING TAPERING HOLES.

Application filed April 9, 1927. Serial No. 182,330.

The invention relates to a machine for boring tapering holes. It has for its principal objects the provision of an improved machine for accomplishing the function stated, which can be operated with great rapidity and precision to give quantity production at a low cost; which is simple in construction; and which can be built and maintained at a low cost. One embodiment 10 of the invention is shown in the accompanying drawings, wherein:

Figure 1 is a plan view (slightly in perspective) with the parts in the position occupied after the tool is withdrawn from the work, the work being shown in section to 15 show the character of the hole bored. Fig. 2 is a partial plan view showing the position of the parts when the hole is being bored. Fig. 3 is a side elevation (slightly in perspective) of the parts in the position of Fig. 1. Fig. 4 is an end elevation with the drill in expanded position, and Fig. 5 is an elevation of the drill end in contracted position.

Referring to the drawings, 1 is a supporting frame or table for the machine, and 2 is the work table supported by means of the guide bars 3, 3, which have the clips 3^b slidingly engaging the upper surfaces of the bars 3^c forming a part of the supporting frame 1. The bars 3, 3 are rigidly secured at their forward ends to the table 2 by means of the members 3^a, and are connected at their other ends by the transverse bar 4. 30 Journalized in the frame 1 is the hollow work spindle 5, which releasably holds the tool bar or shank 6 of the tool, and is driven by the pulleys 5^a and 5^b, 5^c being a loose pulley. The tool comprises the flat center cutter 7, 35 and the two side cutters 8, 8, having laterally extending ends 9, 9 secured rigidly in the forward ends of the links 10, 10. The links 10, 10 are pivoted adjacent their forward ends at 11, 11, upon the cross head 12 integral with the forward end of the tool shank 6. The center cutter 7 fits removably in a socket in the end of the shank 6, being held in position by means of the set screw 13. This permits of the removal of the cutter for replacement or sharpening, or to 50 substitute a cutter of different width.

The rear ends of the links 10, 10 are pivotally connected at 14, 14 to the links 15, 15, and such links are in turn pivoted at their rear ends at 16, 16 to the cross head 17 integral with a collar 18, which is freely

slidable longitudinally of the shank 6. The sliding movement of this collar along the shank is limited by the sleeves 19 and 20, which are secured in any desired position of adjustment by means of set screws 21, 21. Swivelled on the collar 18 is a disc or collar 22. This disc 22 is adapted to be moved back and forth to shift the collar 18, and thus swing the links 10, 10 toward and from the shank 6. This is accomplished by means of the forked lever 23, pivoted on a rod 24, secured in a bracket 24^a, carried by the frame of the machine. Intermediate its ends, the lever is pivotally connected to the sides of 70 the disc 22 by means of the screws 25, 25. The lever is operated, when the work table moves to the left from the position of Fig. 3, by means of the arm 26 carried by the work table, and provided with the adjustable engaging member 27. This member has a pair of rods 28, 28 projecting through the head 29 of the arm 26, and such rods are clamped in position by set screws 30. The position of the member 27 determines the time at which 80 the side cutters are caused to begin their spreading movement to cut the taper for the hole being bored.

In operation, with the parts in the position of Figs. 1 and 3, the rotation of the 85 tool shank and the pairs of links 10, 15, and 10, 15, causes the links to swing out to the position shown by centrifugal force, thus holding the side cutters 8, 8 in tightly against the center cutter 7. With the cutters in this 90 position (see Fig. 5), only the center cutter engages the work, when the work table 2 is moved to the left from the position of Figs. 1 and 3. As a result, a hole A is cut having straight sides (Fig. 1) as long as this condition obtains. When the table 2 moves to the left far enough to cause the member 27 to engage the lever 23, a further movement of the table swings the lever to the left, thus moving the collar 18 to the left and with it 100 the links 15, 15, thus causing the side cutters 8, 8 to spread. This spreading movement continues until the collar 18 strikes the collar 20, and during this period, the expanding side cutters, cut the tapering portion B (Fig. 1) of the hole, the parts at this time occupying the position shown in Fig. 2. To withdraw the tool, the work table 2 is moved to the right, and during the period of withdrawal, centrifugal force spreads the 110 links, thus causing the cutters 8, 8 to approach the center cutter, so that the side cut-

ters are free from the walls of the hole during the withdrawing movement.

It will be seen that the movements of the side cutters are automatic during the boring and withdrawing operations, and that the length of the straight cut portion A of the hole is regulated by the position of the member 27, the length of the taper portion B and the extent of the taper being governed by the position of the collar 20, which may be adjusted to suit requirements. The diameter of the straight portion of the hole may be varied by changing the center cutter 7, while the position of the two stop collars 20 and 21 regulates the size of the taper portion of the hole, so that taper portions of different diameters to correspond to different sizes of center tools, may be bored by the side cutters without changing such cutters. By shifting the two collars to the left, the diameter of the taper portion of the hole is increased. The side cutters are made removable from the links 10, 10 so that they may be readily removed for resharpening or replacement.

What I claim is:

1. In combination in a machine for boring tapering holes, a work table, and a machine support, one of which is movable toward the other, a driven tool bar mounted for rotation in said support, a center boring tool carried thereby, a pair of links pivoted adjacent the forward end of the bar, and each carrying a side cutting tool, a second pair of links pivoted to the rear ends of the first links, a collar movable longitudinally of the spindle and having pivotal engagement with the rear ends of said second pair of links, a pair of stop members mounted on the spindle for longitudinal adjustment thereof, adapted to limit the movement of the collar in both directions, and means operated by the movement of approach of the work table and machine support for moving the collar longitudinally of the spindle and causing the spreading of the side cutters.

2. In combination in a machine for boring tapering holes, a work table, and a machine support, one of which is movable toward the other, a driven tool bar mounted for rotation in said support, a center boring tool carried thereby, a pair of links pivoted adjacent the forward end of the bar, and each carrying a side cutting tool, a second pair of links pivoted to the rear ends of the first links, a collar movable longitudinally of the spindle and having pivotal engagement with the rear ends of said second pair of links, a pair of stop members mounted on the spindle for longitudinal adjustment thereof, adapted to limit the movement of the collar in both directions, and means operated by the movement of approach of the work table and machine support for moving the collar longitudinally of the spindle and causing the

spreading of the side cutters, the said links being arranged so as to move away from the tool bar by centrifugal force, when the tool bar is rotated, causing said collar to engage the forward stop member and the side cutters to move to closed position.

3. In combination in a machine for boring tapering holes, a work table, and a machine support, one of which is movable toward the other, a driven tool bar mounted for rotation in said support, a center boring tool carried thereby, a pair of links pivoted adjacent the forward end of the bar, and each carrying a side cutting tool, a second pair of links pivoted to the rear ends of the first links, a collar movable longitudinally of the spindle and having pivotal engagement with the rear ends of said second pair of links, a pair of stop members mounted on the spindle for longitudinal adjustment thereof, adapted to limit the movement of the collar in both directions, a lever for moving said collar to the rear, and a member carried by the work table and adapted to engage said lever and cause its movement after the movement of approach between the work table and machine support has progressed a predetermined distance.

4. In combination in a machine for boring tapering holes, a work table, and a machine support, one of which is movable toward the other, a driven tool bar mounted for rotation in said support, a center boring tool carried thereby, a pair of links pivoted adjacent the forward end of the bar, and each carrying a side cutting tool, a second pair of links pivoted to the rear ends of the first links, a collar movable longitudinally of the spindle and having pivotal engagement with the rear ends of said second pair of links, a pair of stop members mounted on the spindle for longitudinal adjustment thereof, adapted to limit the movement of the collar in both directions, a lever for moving said collar to the rear, and a member carried by the work table and adapted to engage said lever and cause its movement after the movement of approach between the work table and machine support has progressed a predetermined distance, said member being adjustable in the direction of said movement of approach in order to determine the length of the bore cut by the center tool before the side tools are brought into action.

5. In combination in a machine for boring tapering holes, a work table, and a machine support, one of which is movable toward the other, a driven tool bar mounted for rotation in said support, a center boring tool carried thereby, a pair of links pivoted adjacent the forward end of the bar, and each carrying a side cutting tool, a second pair of links pivoted to the rear ends of the first links, a collar movable longitudinally of the spindle and having pivotal engagement with the rear ends of said second pair of links, a pair of stop members mounted on the spindle for longitudinal adjustment thereof, adapted to limit the movement of the collar in both directions, and means operated by the movement of approach of the work table and machine support for moving the collar longitudinally of the spindle and causing the

of the first links, a collar movable longitudinally of the spindle and having swivelled relation with the rear ends of said second pair of links, a pair of stop members mounted on the spindle for longitudinal adjustment thereof, adapted to limit the movement of the collar in both directions, a lever pivoted to the machine support above the tool bar and to the collar therebelow, and a member carried by the work table and adapted to engage the lower end of said lever and cause its movement after the movement of approach between the work table and machine support has progressed a predetermined distance.

for rotation in said support, a center boring tool carried thereby, a pair of links pivoted adjacent the forward end of the bar, and each carrying a side cutting tool, a second pair of links pivoted to the rear ends of the first links, a collar movable longitudinally of the spindle and having pivotal engagement with the rear ends of said second pair of links, a lever for moving said collar to the rear, and a member carried by the work table and adapted to engage said lever and cause its movement after the movement of approach between the work table and machine support has progressed a predetermined distance.

6. In combination in a machine for boring tapering holes, a work table, and a machine support, one of which is movable toward the other, a driven tool bar mounted

In testimony whereof, I have hereunto subscribed my name this 8th day of April, 1927.

CHARLES D. McARTHUR.
